(57) **CLAIM**

We claim the ornamental designs for a mattress, as shown and described.

DESCRIPTION

FIG. 1 is a perspective view of a mattress showing our new design; and

FIG. 2 is a front elevational view depicting a foot end of the mattress shown in FIG. 1;

FIG. 3 is a right-side elevational view of the mattress shown in FIG. 1, wherein the left side view is a mirror image thereof; and,

FIG. 4 is a back elevational view depicting a head end of the mattress shown in FIG. 1.

1 Claim, 2 Drawing Sheets
